UNITED STATES PATENT OFFICE.

CHARLES A. RICH, OF PROVIDENCE, RHODE ISLAND, ASSIGNOR TO BROWN AND SHARPE MANUFACTURING COMPANY, OF PROVIDENCE, RHODE ISLAND, A CORPORATION OF RHODE ISLAND.

MILLING-MACHINE.

1,355,167.

Specification of Letters Patent. Patented Oct. 12, 1920.

Application filed March 8, 1918. Serial No. 221,109.

To all whom it may concern:

Be it known that I, CHARLES A. RICH, a citizen of the United States, residing at Providence, in the county of Providence and State of Rhode Island, have invented certain new and useful Improvements in Milling-Machines; and I do hereby declare the following to be a full, clear, and exact description of the invention, such as will enable others skilled in the art to which it appertains to make and use the same.

The invention relates primarily to automatic milling machines, although some of its features are applicable to other machines.

Automatic milling machines are particularly designed for successively milling large numbers of duplicate pieces. Work of this class is usually done by "automatic milling", by "intermittent milling", or by "continuous milling". In automatic milling the work supporting table is fed at a fast speed to bring the work up to the cutter, then at a slow speed during the cutting, is then reversed and returned at a fast speed to its starting point, and is then stopped, all of these operations being automatically effected. In intermittent milling several pieces of work or several spaced surfaces on the same piece are successively milled during the forward travel of the table, and in this case there may be a fast feed of the table to bring each piece or surface up to the cutter after the preceding piece or surface has been milled, as well as a fast feed to bring the first piece up to the cutter. In continuous milling a piece of work is milled during the travel of the table in each direction, and the operator removes a finished piece from each end of the table and replaces it with another, while a piece of work at the other end of the table is being milled. In this case the table may be reversed at each end of its travel and may be fed at a fast speed during the first part of its travel in each direction to bring the unfinished piece of work up to the cutter, and at a slow speed during the remainder of its travel while the cutter is milling this piece of work.

It is the primary object of the invention to provide an improved mechanical control for the work supporting table and co-operating parts which will adapt the machine to do any of the forms of milling outlined

above. To this end a feature of the invention consists in transmitting motion to the work supporting table through a mechanical feed train including mechanism for changing the speed and for changing the direction of travel of the table, which may be so controlled by tripping devices, such as tripping dogs, connected to move with or in unison with the support, that the table may be reversed when traveling at a slow speed or at a fast speed, and the speed of the support may be changed during its travel in each direction. The mechanism for changing the direction of travel of the support, and the mechanism for imparting a fast or slow feed to the support, are preferably so arranged in the train that motion is transmitted to the support from one of these mechanisms through the other. This enables the feed to be readily changed from fast to slow and from slow to fast at any desired point or points in the travel of the support in either direction by proper adjustment of the tripping dogs, and without affecting the mechanism for reversing or stopping the support, the operation of which may be independently controlled by the corresponding tripping dogs.

In doing some classes of work it is desirable that the rotation of the cutter spindle be stopped during the return travel of the finished work past the cutter in order to avoid marking the milled surfaces. To secure this result without interfering with the automatic operation of the machine, mechanism is provided for stopping and starting the spindle, which may be so controlled that the spindle stops as the work support is automatically reversed, and again starts before or at the same time that an unfinished piece of work is presented to the cutter. The spindle stopping and starting mechanism is preferably thus controlled by the speed changing mechanism, or by the speed changing and the reversing mechanisms for the work support through connections which when active will cause the spindle to be stopped as the support is reversed, and to be started as the change is made from the fast to the slow feed. The spindle may therefore be stopped in automatic or intermittent milling as the support is reversed at the end of its forward travel, and be again started as the feed is changed from

- fast to slow after the work is brought up to the cutter at the beginning of the next forward travel of the support. In continuous milling the spindle may be stopped as the support is reversed at each end of its travel, and again started as the feed is changed from fast to slow after the support has partially completed its travel in either direction.
- 10 In continuous milling, the pieces of work on opposite ends of the support are fed to the cutter in opposite directions, and if a plain or form cutter were used in machines as heretofore constructed the cutter would cut against the feed in the proper manner during the forward travel of the table, but during the return travel of the table the cutter would cut with the feed, a condition which has proved to be unsatisfactory for practically all classes of work. It has been customary, therefore, to use end mills or cutters when doing continuous milling, and this manner of milling has been confined to work which is adapted for this type of cutter.
- 15 A feature of the invention which enables continuous milling to be successfully done with plain or form milling cutters, and thus adapts the machine for work which could not heretofore be done in this manner, consists in the provision of mechanism for reversing the direction of rotation of the cutter spindle which may be so controlled that the spindle is rotated during the return travel of the work support in a direction opposite to that in which it is rotated during the forward travel of the support. Two oppositely arranged cutters may then be secured on the spindle to operate on the work on opposite ends of the support, and each cutter may be rotated to cut against the feed during the milling action. The spindle reversing mechanism is preferably operated from the mechanism for reversing the work support, so that both reversing mechanisms are simultaneously operated as the work support reaches the end of its travel in each direction. The spindle reversing mechanism may be rendered active or inactive at the will of the operator, and may be used with or without the spindle stopping mechanism.
- 20 The features outlined above, as well as the further features of invention which are defined in the claims, are illustrated in the accompanying drawings, in which Figure 1 is a right-hand side elevation of a milling machine embodying all the features of the invention in their preferred forms; Fig. 2 is a left-hand side elevation of the machine; Fig. 3 is a partial front view showing the machine set up for intermittent milling; Fig. 4 is a similar view showing the machine set up for continuous milling; Fig. 5 is a partial end view of the work supporting table looking toward the right in Fig. 3;

Fig. 6 is a sectional elevation on the broken line 6—6 of Fig. 7; Fig. 7 is a sectional elevation on the line 7 of Fig. 6; Fig. 8 is a horizontal sectional view on line 8—8, Figs. 2 and 7; Fig. 9 is a detail showing the means for rendering the spindle reversing mechanism inactive; Fig. 10 is a detail elevation looking toward the left in Fig. 8, showing the clutch for the speed changing cam; Fig. 11 is a sectional elevation on line 11—11, Fig. 6; Fig. 12 is a horizontal sectional view on line 12, Fig. 1; Fig. 13 is a horizontal sectional view on line 13—13, Fig. 1; Fig. 14 is a horizontal sectional view on line 14—14, Fig. 1; and Fig. 15 is a vertical sectional view on line 15—15, Fig. 13.

The milling machine shown in the drawings is provided with a rotary cutter spindle 2 and a work support table 4 mounted to reciprocate in a transversely movable saddle 6 which is in turn mounted upon a vertically movable knee 8. Motion is transmitted to the table through a mechanical feed train which includes mechanism for feeding the table at fast and slow speeds, and mechanism for reversing the direction of the travel of the table. As shown, the feed train comprises a vertical shaft 10 mounted in the saddle, and provided at its upper end with a pinion 12 engaging a rack on the table, and provided at its lower end with a bevel gear 16 which is engaged by a pinion 18 on the end of a horizontal shaft 20 (Figs. 3 and 4). The fast and slow feed mechanism is mounted on the saddle, and as indicated in Figs. 1 and 13 to 15, comprises a shaft 22 provided with a pinion 24 engaging a gear 26 on the shaft 20, and also provided with a clutch 28 which may be engaged with either a fast or slow speed train of gearing. The clutch is pinned to the shaft and is arranged between a fast speed gear 30 and a slow speed worm wheel 32 which are loosely mounted on the shaft. The fast speed gear 30 is a spiral gear, and is engaged and driven by a similar gear 34 secured to a shaft 36 which underlies the shaft 22 and is driven through an extensible shaft 38 and universal joints 40 and 42 from a shaft 44 which is mounted on a fixed part of the machine and is shown in Fig. 6. The slow speed worm wheel 32 is engaged by a worm 46 secured to a shaft 48 which is driven from the shaft 36 through a system of change gears 50 which may be adjusted to vary the slow feed given to the table during the action of the cutter on the work.

The clutch 28 is shifted to change the speed of the feed by an intermittently rotating cam 52 loosely mounted on a fixed shaft 54 and engaging a clutch shifting lever 56. The lever is connected to a rock shaft 58 provided with a gear segment engaging a rack formed on a sleeve 60 which is mounted on the end of the shaft 22. A

spring 62 forms a yielding connection between the sleeve and shaft which may yield in case the clutch teeth land when the cam is operated to shift the clutch. The means 5 for operating the clutch shifting cam comprises a clutch sleeve 64 connected with the cam by a sliding coupling 66 and forced by a spring 68 in a direction to engage its clutch teeth with the clutch teeth formed on a 10 gear 70. The gear 70 is a spiral gear loosely mounted on the fixed shaft 54 and driven from the shaft 36 through a similar gear 72. The engagement and disengagement of the clutch 64, and consequently the shifting 15 of the speed changing clutch 28, is controlled by two plungers 74 and 76 arranged to be moved alternately into and out of the path of two diametrically opposite cams 78 and 80 on the clutch sleeve 64. With the 20 parts in the position shown in Figs. 13 and 15, the clutch is held out of engagement by the cam 78 and plunger 74, and the speed changing clutch 28 is in engagement with the fast speed gear 30. When the feed is to 25 be changed from fast to slow, the plunger 74 is retracted to withdraw it from engagement with the cam 78, and the plunger 76 is advanced into the path of the cam 80, so that the clutch 64 is engaged, is driven 30 through a half revolution, and is then disengaged by the engagement of the cam 80 with the plunger 76. In a similar manner the feed may be changed from slow to fast by withdrawing the plunger 76 and advancing the plunger 74, so that the clutch 35 64 will turn the clutch shifting cam through a half revolution and shift the speed changing clutch from the slow speed worm wheel to the fast speed gear. The plungers may 40 be alternately advanced and retracted through a horizontal rock shaft 82 provided with a pinion 84 engaging circular racks 86 on the plungers. The rock shaft extends beyond the front side of the saddle 45 and is provided at its outer end with a handle 88 through which it may be manually operated to shift the plungers. The rock shaft may be automatically rocked through vertical tripping plungers 90 and 50 92 which are provided with rack teeth engaging a pinion 94 on the shaft, and are provided with upper V-shaped ends arranged to project into the paths of tripping dogs 96 and 98 which are connected to move 55 in unison with the table, preferably by being adjustably secured to guideways formed on the side of the table. The plungers are arranged out of alinement with each other lengthwise of the table, and the dogs 96 are 60 arranged to engage and depress the plunger 92, while the dogs 98 are arranged to engage and depress the plunger 90. The parts are so arranged that the table will be fed at fast speed when the plunger 90 is 65 down and the plunger 92 is up, and the

table will be fed at a slow speed when the plunger 92 is down and the plunger 90 up. The dogs 98, therefore, which act to depress the plunger 90, may be adjusted to change the feed from slow to fast at any 70 point in the travel of the table in either direction, and the dogs 96 which depress the plungers 92 may be adjusted to change the feed from fast to slow at any point in the travel of the table in either direction. The 75 dogs 96 as shown are one-way dogs which will act to depress the plunger 92 during the travel of the table in one direction, but will ride idly over the plunger during the travel of the table in the other direction, 80 since it is usually undesirable to change the feed from fast to slow at the same point in the travel of the table in each direction.

The mechanism for reversing the direction of travel of the table comprises a reversing clutch 100 connected to slide on and to rotate the shaft 44 through which motion is transmitted to the fast and slow feed mechanism on the saddle (Fig. 6). The clutch is arranged between and is adapted 85 to be engaged with either a forward drive clutch member 102 or a return drive clutch member 104. The clutch member 102 is driven continuously from a pinion 106 on the driving shaft 108 through an intermediate gear 110 which engages a gear 112 secured to the clutch member. The return clutch member 104 is continuously driven in a reverse direction through an intermediate bevel gear 114 which engages a bevel 95 gear formed on the gear 112 and a bevel gear 116 secured to the return clutch member. 100

The reversing clutch is shifted through a lever 118 which is operated by a cam 105 groove 120 formed in a cam sleeve 122 which may be given a half revolution to shift the reversing clutch from one clutch driving member to the other, or may be given successive quarter turns to shift the clutch 110 from one driving clutch member into neutral position, and then from neutral position into engagement with the other driving clutch member. The mechanism for intermittently rotating the cam sleeve is similar to the mechanism for rotating the speed clutch cam 52 already described, and comprises a clutch sleeve 124 connected with the cam sleeve and intermittently engaged with a continuously rotating clutch member 126 secured to the shaft 128 on which the clutch sleeve and cam sleeve are loosely mounted. The shaft is continuously driven through a gear 130 which engages the gear 112. In this construction the cams 132 and 134 on the clutch sleeve, which coöperate with the plungers 136 and 138 in controlling the engagement and disengagement of the clutch are two-stepped cams, each cam being provided with a low part and a high 130

part, as indicated in Figs. 8 and 10, the low part on one cam being 90° in advance of the high part of the same cam, and the low and high parts of each cam being diametrically opposite the low and high parts of the other cam. Each plunger is also provided with two stepped surfaces 140 and 142 adapted to coöperate successively with the two steps of the corresponding two-stepped cam during the advance and withdrawal of the plungers, and with a single surface 144 adapted to coöperate with a single step of the cam during the advance and withdrawal of the plungers. If the plungers are positioned as indicated in Figs. 8 and 10, so that the single surfaces 144 are in active relation to the cams 132 and 134, the clutch sleeve and reversing clutch shifting cam will be given successive half revolutions by alternately advancing and retracting the plungers. With the parts in the position shown, the clutch sleeve 124 is held out of engagement with the clutch member 126 by the engagement of the low part of the cam 132 with the plunger 136, and the reversing clutch is in engagement with the return drive clutch member 104 and the table is traveling from right to left. When the travel of the table is to be reversed, the plunger 136 is retracted to disengage the surface 144 from the low part of the cam 132, and the plunger 138 is advanced to bring its surface 144 into the path of the low part of the cam 134, so that the clutch shifting cam will make a half revolution. In the same way the clutch is shifted to reverse the table at the other end of its travel by retracting the plunger 138 and advancing the plunger 136. If the table is to be stopped at the end of its travel from right to left and subsequently started in the opposite direction, the plunger 136 may be turned to bring its two-stepped surface 140 and 142 into active relation to the cam 132. Then with the parts in the same position as indicated in Figs. 8 and 10, the surface 142 on the plunger 136 will be engaged by the low part of the cam 132. When the table reaches the end of its travel from right to left, the plunger 136 will be retracted until the surface 142 disengages the low part of the cam 132, thus allowing the clutch sleeve 126 to engage the clutch member 124. The clutch sleeve will now be driven through a quarter revolution, or until the high part of the cam 132 engages the surface 140 on the plunger 136, when the clutch sleeve will be disengaged. The reversing clutch cam will therefore be given but a quarter revolution, and the clutch will be shifted into mid-position to stop the table. When the table is to be started, the withdrawal of the plunger 136 will be completed, thus disengaging its surface 140 from the high part of the cam 132 and

bringing the surface 144 (or the surface 142, as the case may be) into the path of the low part of the cam 134, which is 90° behind the high part of the cam 132. The reversing clutch cam will therefore be given 70 another quarter revolution to complete the shifting of the clutch and thus start the table in the opposite direction. By similarly adjusting the plunger 138 the table may be stopped and started in the same 75 manner at the other end of its travel.

The plungers 136 and 138 are retracted and advanced by two intermeshing pinions 146 and 148 which engage racks formed on the plungers. The plungers are held in adjusted position by pins 150 arranged to engage one or the other of two diametrically opposite grooves 152 formed in the plungers. Each plunger is provided with a handle 154 by which it may be conveniently 80 turned through a half revolution to bring either groove 152 into position to be engaged by the pin 150, the pin being withdrawn to permit the adjustment of the plunger. The pinions 146 and 148 are rocked to 85 operate the plungers through a rock shaft 156 mounted on the saddle and connected with the pinion 146 through an extensible shaft 158 and universal joints 160 (Fig. 2). The rock shaft 156 projects beyond the front 90 side of the saddle, and is provided with a handle 162 by which the operator may rock the shaft to manually control the shifting of the table reversing clutch. The shaft may be automatically rocked to reverse or stop 95 the table through tripping plungers 164 and 166 which are provided with racks engaging a pinion 168 on the rock shaft, and are provided with V-shaped upper ends arranged to be engaged by tripping dogs 170 and 172 100 which are connected to move with the table preferably by being adjustably secured on the side of the table (Figs. 3, 4 and 5). If both dogs 170 and 172 are long dogs, as indicated in Fig. 4, the tripping plungers 110 will be operated to retract and advance the controlling plungers 136 and 138 in a single stage movement to reverse the table at the end of its travel in each direction. If one of the dogs is a short dog, as indicated at 172 115 in Fig. 3, while the other dog is a long dog, as indicated at 170, then the table will be reversed at the end of its travel toward the right, but at the end of its travel toward the left the short dog 172 will only partially 120 depress the plunger 164, thus partially retracting and advancing the controlling plungers to effect the stopping of the table. The table may be reversed even with the plungers 136 and 138 adjusted in the reverse position to that indicated in Fig. 8, provided the table is being fed at the fast speed when the tripping dog 170 or 172 acts on the tripping plungers. In this case the withdrawal of the plunger 136 and advance 125 130

of the plunger 138 is rapid enough to complete the withdrawal of the plunger 136 before the high step of the cam 132 comes into position to act upon the surface 140 of that plunger. The result will be that the clutch 126 will make a half revolution before it is disengaged from the clutch member 124 instead of a quarter revolution, as would be the case if the plunger 136 were withdrawn by the trip dog during the slow feed of the table. It is usually desirable, however, to adjust the plungers 136 or 138 as above indicated, so that the clutch will be given a half revolution and thus reverse the table, regardless of the speed at which the plungers are retracted and advanced, since by this adjustment the table may be reversed at the end of a cut without first changing the feed of the table from slow to fast.

20 The mechanism through which motion is transmitted to the spindle 2 comprises mechanism which may be rendered active or inactive at the will of the operator for stopping the spindle during the fast feed of the table 25 in either direction, and mechanism which may be rendered active or inactive at the will of the operator for reversing the direction of rotation of the spindle. As shown in Figs. 6, 7 and 11, the driving shaft 108 is connected by couplings indicated at 174 in Fig. 6 with a driving member 176 adapted to be connected or disconnected with the hollow shaft or sleeve 178 by a clutch indicated generally at 180. The clutch is a double 30 clutch arranged between the driving member 176 and a stationary member 182 which is connected with the machine frame. The clutch is shifted to connect the shaft 178 with the driving member 176, so that the 35 spindle is rotated, or to frictionally connect the shaft with the stationary member 182 so that the rotation of the spindle is stopped. The means for thus shifting the clutch comprises a rock shaft 184 provided at one end 40 with a clutch engaging yoke 186, and at the other end with an arm 188, the lower end of which carries a roll 190 engaging a clutch shifting cam 192. The mechanism for intermittently operating the clutch shifting 45 cam 192 is similar to the mechanism for operating the clutch shifting cam 52, and comprises the clutch sleeve 194 adapted to intermittently engage the continuously rotating clutch member 196, and controlled by the 50 plungers 198 which are alternately advanced and retracted into and out of the paths of diametrically opposite cams 200 on the clutch sleeve. The clutch member 196 is secured to a shaft 202 on which the clutch and 55 cam sleeves are mounted, and is driven continuously through a gear 204 engaging the intermediate gear 110. The plungers are retracted and advanced by two intermeshing pinions 206 and 208 which are operated from 60 the rock shaft 82 through an extensible shaft 65 210 and universal joints 212 (Fig. 1). The controlling plungers 198 may thus be retracted and advanced to effect the starting and stopping of the spindle when the shaft 82 is rocked to change the feed of the table 70 from fast to slow or slow to fast. The plungers 198 and cams 200 are preferably so proportioned with relation to the plungers 74 and 76 which control the fast and slow speed clutch that the plungers 74 and 75 76 are moved sufficiently to effect a change in the feed of the table before the plungers 198 have been moved sufficiently to effect a change in the position of the spindle starting and stopping clutch. By properly proportioning or adjusting the tripping dogs 80 98 therefore, changes from slow to fast feed may be effected at certain points in the travel of the table without stopping the spindle, while the change from slow to fast feed at 85 other points in the travel of the table will result in a stopping of the spindle.

The mechanism for starting and stopping the spindle may be rendered inactive by the operator by turning a rock shaft 214 into 90 such position that an eccentric stop pin 216 on its rear end will engage a flange 218 on the clutch sleeve 194 and prevent its engagement with the member 196 when the plungers 198 are retracted and advanced. 95 By turning the rock shaft 214 through a half revolution, the eccentric stop pin 216 is moved out of active position, and thus the spindle stopping and starting mechanism 100 is rendered active.

The mechanism for reversing the direction of rotation of the spindle comprises a clutch indicated generally at 220 which is connected to the hollow shaft 178 and is arranged between two oppositely arranged 105 bevel gears 222 which are loosely mounted on the shaft 178, and are provided with clutch members 224 arranged to be alternately engaged by the clutch 220 (Fig. 6). The gears 222 engage the opposite sides of 110 a bevel gear 226. The gear 226 is secured to the inner end of a short shaft, the outer end of which carries a gear 228 forming one of a series of change gears 230 through which motion is transmitted to a shaft 232 (Figs. 1 115 and 11). The inner end of the shaft 232 carries a bevel gear 234 which meshes with a gear 236 on the spindle.

The mechanism for shifting the clutch 120 220 from one member 224 to the other to reverse the spindle comprises a rock shaft 238 provided with a clutch engaging yoke and with a depending arm 240. The lower end of the arm is connected to one end of a link 242, the other end of which is provided with 125 a notch 244 adapted to engage a pin 246 on the upper end of a clutch shifting lever 248 (Figs. 6, 7 and 9). The lower end of the lever 248 is provided with a roll arranged to be engaged by cams 250 on the cam sleeve 130

122. The cams 250 are so arranged with relation to the cam groove 120 that the spindle reversing clutch will be shifted to reverse the spindle when the reversing clutch 100 for the work supporting table is shifted to reverse the direction of travel of the table. The mechanism for rotating the spindle in opposite directions during the forward and return travel of the table enables plain 10 or form milling cutters to be arranged on the spindle to act upon work on the table during its return as well as during its forward movement. Thus two oppositely arranged cutters 252 and 254 such as indicated 15 in Figs. 1 and 4, may be secured upon the spindle so that they are out of line with each other lengthwise of the table, and the spindle may be rotated clockwise during the forward travel of the table from left to 20 right, so that the cutter 254 will act against the feed during the milling of a piece of work 256, and may be rotated contra-clockwise during the travel of the table from right to left, so that the cutter 252 will act 25 against the feed during the milling of the piece of work 258. The automatic reversal of the spindle when the table is reversed enables continuous milling to be done with plain or form cutters which may be secured 30 to the spindle, as indicated in Figs. 1 and 4, and rotated in a direction to act against the feed during the slow travel of the table in either direction.

The mechanism for automatically reversing the spindle may be rendered active or inactive at the will of the operator by manipulation of a rock shaft 260 (Figs. 7 and 9). The inner end of the rock shaft is provided with an eccentric cam projection 262 arranged to engage the end of the link 242 and disengage the notch 244 from the pin 246, thus disconnecting the link from the clutch shifting lever 248. The link may be disconnected when the clutch 220 is in engagement 45 with either of the clutch members 224, and the spindle may therefore be continuously driven in either direction.

When the work supporting table is reversed the beginning of its movement in the 50 reverse direction should usually if not always be at the fast speed. It is desirable therefore that the fast speed feed should be rendered active whenever the table is reversed. This is particularly so when milling 55 up to a shoulder, since in this case the slow feed must continue to the end of the travel of the table. In order that the fast feed may be automatically rendered active whenever the table is reversed, means is provided 60 for controlling the change from slow to fast speed from the table reversing mechanism. In the construction shown this means comprises two cams 264 formed on the clutch sleeve 124, and therefore connected to rotate 65 with the cam 120 which shifts the table re-

versing clutch 100. The cams 264 are arranged to operate a vertically movable rod 266, the upper end of which is provided with a rack engaging the pinion 206 (Figs. 1, 6 and 12). As already described, this pinion 70 is connected through the pinion 208 and shaft 210 with the rock shaft 82 which retracts and advances the plungers 74 and 76 which control the speed of the table feed. The parts are shown in the drawings in the 75 positions which they occupy when the fast feed is in action and the rod 266 is in its raised position. One of the cams 264 has passed from under the rod so that it is free to move downward when the table feed is 80 changed from fast to slow by rocking the shaft 82, which movement is accompanied by a partial rotation of the pinions 208 and 206 and the withdrawal of one of the plungers 198 and the advance of the other, as 85 heretofore described. During the half (or quarter) revolution of the cam sleeve 122 which shifts the table reversing clutch 100 into the clutch member 102 and thus reverses the table, the cam 264 shown at the 90 lower side of the clutch sleeve 124 in Fig. 6 rides under the rod 266 and raises it into the position indicated in the drawings. This movement of the rod rotates the pinions 206 and 208 and rocks the shaft 82 to withdraw 95 the plunger 76 and advance the plunger 74 so that the feed of the table is changed from slow to fast as the table is reversed.

Since the connection between the table reversing mechanism and the change speed 100 mechanism is through the pinions 206 and 208, the spindle stopping and starting mechanism may also be controlled from the table reversing mechanism to stop the spindle whenever the table is reversed. In this case 105 the spindle stopping and starting mechanism will be controlled from the speed changing mechanism to start the spindle when the table feed is changed from fast to slow as previously described. In doing continuous milling, therefore, the table may be automatically reversed at each end of its 110 travel in either direction, and fed at a fast speed during the first part of each reverse movement, and the spindle may or may not be stopped as the table is reversed, and if stopped it may be again started when the feed is changed from fast to slow after the table has partially completed its movement in either direction. By its connection with 115 the table reversing mechanism, the spindle reversing clutch may also be shifted when the table is reversed so that when started the spindle will rotate in a direction the reverse of that in which it rotated during the 120 travel of the table in the opposite direction.

By proper arrangement and adjustment of the tripping dogs which act upon the tripping plungers 90 and 92 and 164 and 166, the various mechanisms of the machine 130

may be automatically controlled in accordance with the character of the work to be done. For instance, in Fig. 3 an adjustment and arrangement of tripping dogs suitable 5 for controlling the mechanisms of the machine in doing intermittent milling is shown. As here shown, the table is moving in the direction of the arrow, or toward the right, and the milling cutter has just 10 finished milling the second piece of work secured on the table. The second dog 98 has partially depressed the tripping plunger 90, and the feed of the table is about to be changed from slow to fast through the controlling devices already described. After 15 the plunger 90 is depressed by the dog 98 the travel of the table will be at a fast speed until the third dog 96 engages the plunger 92 and depresses it. The feed of the table will then be changed from fast to slow, and 20 this will occur just as the third piece of work is brought up to the cutter. The slow feed will continue during the milling of this piece, and then the third dog 98 will act on 25 the plunger 90 to again change the feed from slow to fast. This alternate change of feed from fast to slow and slow to fast will continue until all of the pieces of work have been acted on by the cutter. As the 30 last piece is finished the reversing dog 170 will engage the plunger 166 and depress it, thus shifting the plungers 136 and 138 which control the clutch sleeve 124, so that the clutch sleeve and the cams connected 35 therewith will be given a half revolution to reverse the table, change the feed from slow to fast, and to stop the spindle in case the spindle stopping and starting mechanism is active. The change from slow to fast feed 40 will raise the plunger 90 and depress the plunger 92. The table will be returned at fast speed until the stop dog 172 engages the plunger 164 and partially depresses it to partially withdraw and advance the 45 plungers 136 and 138, so that the clutch sleeve 124 and cams connected therewith will be given a quarter turn to shift the table reversing clutch into midposition. During the return of the table the dogs 96 50 will swing about their pivots and ride idly over the plunger 92. In case it is desired to stop the spindle during the return travel of the table and not stop the spindle when the feed is changed from slow to fast during 55 the forward or cutting stroke of the table, the dogs 98 may be of such a length or so adjusted that the movement transmitted through the plunger 90, while sufficient to effect the changing of the speed, is 60 not sufficient to effect the shifting of the spindle stopping and starting clutch. After the finished work has been removed and new pieces of work secured on the table, the table may be started in the reverse direction, or toward the right, by shifting the 65 handle 164 into the position indicated in Fig. 3. This movement of the handle will complete the movement of the plungers 166 and 168, so that the clutch sleeve 124 and the cams connected thereto will be given a 70 second quarter revolution to complete the shifting of the table reversing clutch. The table will be moved at fast speed, and the spindle stopping clutch will remain in stopped position until the first tripping dog 75 96 acts upon the plunger 92. The depression of this plunger by the dog will change the speed from fast to slow, and through the connections described will shift the plungers 198 to give the spindle stopping 80 clutch cam a half revolution and thus start the spindle. The feed of the table will then be alternately changed from slow to fast and fast to slow during the travel of the table, as above described. 85

In Fig. 4 an arrangement of tripping dogs requisite for doing continuous milling is shown. As here shown the dogs 170 and 172 which operate on the plungers 166 and 168 as the table completes its travel in either 90 direction are both reversing dogs, and the operations described with reference to the arrangement shown in Fig. 3 occur at each end of the travel of the table, instead of only at the end of its forward stroke. In 95 this case there is but one change in the speed of the feed during the travel of the table in each direction, namely the change from fast to slow as each piece of work is brought up to its cutter. Two one-way dogs 100 96 are therefore secured to the table and are oppositely arranged so that the right-hand dog acts upon the plunger 92 during the travel of the table toward the left, and rides idly over the plunger during the travel of 105 the table toward the right, while the left-hand dog acts to depress the plunger during the travel of the table toward the right, and rides idly over the plunger during the travel of the table toward the left. In case 110 plain milling or form cutters such as shown in Figs. 1 and 4 are used, the spindle reversing mechanism is rendered active and the spindle stopping mechanism may be rendered active or not as best suited to the 115 work.

While it is preferred to employ the specific construction and arrangements of parts shown and described, since this construction and arrangement is well adapted for convenient adjustment and manipulation by the operator in setting up the machine for various classes of work, and since this construction and arrangement enables the various mechanisms to be controlled and operated 120 by comparatively few tripping dogs which may be conveniently adjusted to secure any desired mode of operation, it will be understood that this construction and arrangement is not essential to the broader features 125 130

of the invention, and may be varied or modified as found desirable or best suited to the construction of machine in which it is to be embodied, and for the results which it is desired to obtain. It will also be understood that some of the features of the invention may be embodied with advantage in machines without including all the features. It will also be understood that certain features of the invention are not confined in their application to machines in which the various mechanisms are mechanically driven and mechanically controlled, but may be embodied with advantage in machines in which other types of driving or controlling mechanisms are employed.

What is claimed is:—

1. A machine of the class described having, in combination, a traveling support, a mechanical train through which motion is transmitted to the support including mechanisms for changing the direction and for changing the speed of travel of the support so arranged in the train that motion is transmitted from one mechanism through the other, and means including tripping devices connected to move in unison with the support for changing the speed of the support during its travel in each direction and for reversing its direction of travel when moving at either fast or slow speed.

2. A machine of the class described, having, in combination, a traveling support, a mechanical train through which motion is transmitted to the support including mechanism for changing the direction of travel of the support and mechanism for changing the speed of travel of the support so arranged in the train that motion is transmitted from one mechanism through the other, and means including tripping devices connected to move in unison with the support for controlling said mechanism to stop or reverse the support when traveling at fast or slow speed.

3. A machine of the class described, having, in combination, a traveling support, a mechanical train through which motion is transmitted to the support including a motion changing clutch and a speed changing clutch, mechanism including tripping devices connected to move in unison with the support for shifting the motion changing clutch when the support is traveling at either fast or slow speed to reverse the travel of the support, and mechanism including tripping devices connected to move in unison with the support for shifting the speed changing clutch to change the speed of the table during its travel in either direction.

4. A machine of the class described, having, in combination, a traveling support, a mechanical train through which motion is transmitted to the support including a mo-

tion changing clutch and a speed changing clutch, clutch shifting cams, clutches for operating the cams, and means for engaging and disengaging the cam operating clutches including tripping devices connected to move in unison with the support.

5. A machine of the class described, having, in combination, a traveling support, mechanism for imparting a fast or slow feed movement to the support including a clutch which is shifted to change the speed, a clutch shifting cam, a cam operating clutch, and means for engaging and disengaging the latter clutch including tripping devices connected to move in unison with the support.

6. A machine of the class described, having, in combination, a traveling support, mechanism for imparting forward and return movements to the support including a clutch which is shifted to reverse the support, a clutch shifting cam, a cam operating clutch, and means for engaging and disengaging the latter clutch including tripping devices connected to move in unison with the support.

7. A machine of the class described, having, in combination, a traveling support, mechanism for imparting forward and return movements to the support including a clutch which is shifted to reverse or partially shifted to stop the support, a clutch shifting cam, a clutch for operating the cam, devices for controlling the latter clutch to reverse or stop the support including tripping devices connected to move in unison with the support.

8. A machine of the class described, having, in combination, a traveling support, mechanism for imparting forward and return movements to the support including a clutch which is shifted to reverse or partially shifted to stop the support, a clutch shifting cam, a clutch for operating the cam, plungers and coöperating cams on the clutch shifting cam for controlling said clutch, and means for alternately moving the plungers into and out of the path of the cams including tripping dogs connected to move in unison with the support.

9. A machine of the class described, having, in combination, a traveling support, mechanism for imparting forward and return movements to the support including a clutch which is shifted to reverse or partially shifted to stop the support, a clutch shifting cam, a clutch for operating the cam provided with two diametrically opposed two-stepped cams, two plungers arranged to move alternately into and out of the path of the cams, and means for alternately advancing and retracting the plungers including tripping dogs connected to move in unison with the support and acting to partially retract one plunger and advance the other to

stop the support or to completely retract one plunger and advance the other to reverse the support.

10. A machine of the class described, having, in combination, a traveling support, mechanism for imparting forward and return movements to the support including a clutch which is shifted to reverse or partially shifted to stop the support, a clutch 5 shifting cam, a clutch for operating the cam provided with two diametrically opposed two-stepped cams, two plungers arranged for movement alternately into and out of the cam paths, each plunger being provided 10 with two stepped surfaces adapted to cooperate successively with the two steps of the corresponding two-stepped cam during the advance and return of the plunger and with a single surface adapted to cooperate 15 with a single step of the cam during the advance and return of the plunger, means whereby the plungers may be adjusted to bring either the two-stepped surface or the single surface into cooperative relation to 20 the cams, and means for advancing and retracting the plungers including trip dogs connected to move with the support.

11. A machine of the class described, having, in combination, a traveling support, 25 mechanism for imparting forward and return movements to the support including a reversing clutch, a clutch shifting cam, a cam operating clutch, and means for controlling the clutch to impart either quarter 30 turns to the cam to successively stop and reverse the support or half turns to reverse the support.

12. A machine of the class described, having, in combination, a traveling support, 35 mechanism for transmitting motion to the support comprising a fast speed train and a slow speed train, change speed gearing included in the slow speed train, a clutch for rendering either train active, a cam for shifting the clutch, a cam operating clutch, and means for engaging and disengaging the cam operating clutch including tripping devices connected to move in unison with the support.

13. A machine of the class described, having, in combination, a traveling support, mechanism for transmitting motion to the support comprising a forward drive train and a return drive train, a fast speed train 45 and a slow speed train, change speed gearing included in the slow speed train, a clutch for rendering the fast or slow train active, a clutch for rendering the forward or return drive train active, and means controlled by tripping devices connected to move in unison with the support for shifting either clutch from one train to the other when the other clutch is connected with either train.

14. A machine of the class described, having, in combination, a traveling support,

mechanism for transmitting motion to the support comprising forward and return drive trains and fast and slow speed trains, a clutch for rendering the forward and return drive trains alternately active, a clutch 70 for rendering the fast and slow trains alternately active, and controlling means including tripping devices connected to move in unison with the support for shifting either clutch from one train to the other when the 75 other clutch is connected with either train.

15. A machine of the class described, having, in combination, a traveling support, mechanism for transmitting motion to the support including forward and return drive 80 trains and fast and slow speed trains, mechanism for rendering the fast and slow trains alternately active including tripping devices connected to move in unison with the support, mechanism for rendering the forward 85 and return trains alternately active including tripping devices connected to move in unison with the support, and connections through which the latter mechanism renders the fast train active whenever the forward 90 or return train is rendered active to reverse the direction of travel of the support.

16. A machine of the class described, having, in combination, a traveling support, mechanism through which motion is transmitted to the support including a motion changing clutch and a speed changing clutch, mechanism for shifting the motion changing clutch to reverse the direction of travel of the support including tripping devices connected to move in unison with the support, mechanism for shifting the speed changing clutch including tripping devices connected to travel in unison with the support, and connections between the latter 105 clutch shifting mechanism and the former clutch shifting mechanism to render the fast speed active whenever the motion changing clutch is shifted to reverse the travel of the support.

17. A machine of the class described, having, in combination, a traveling support, mechanism through which motion is transmitted to the support including a motion changing clutch and a speed changing 115 clutch, cams for shifting the clutches to reverse the direction and to change the speed of travel of the support, clutches for operating the cams, means for controlling the engagement and disengagement of the clutches including tripping devices connected to move with the support, and connections between the motion changing cam and the controlling means for the change speed cam clutch for bringing the cam into fast speed 120 position when the motion changing cam is moved to reverse the direction of travel of the support.

18. A machine of the class described, having, in combination, a traveling support, 130

mechanism for transmitting motion to the support comprising forward and return drive trains and fast and slow speed trains, a clutch for engaging and rendering active 5 either the forward or return train, a clutch for engaging and rendering active either the fast or slow train, a cam for shifting the change speed clutch, a clutch for operating the cam, controlling devices for the latter clutch including trips connected to move in unison with the support, a cam for shifting the motion changing clutch, a clutch for operating the cam, controlling devices for the clutch including trips connected to move in 10 unison with the support, and connections for operating the controlling devices for the speed changing cam clutch from the motion changing cam clutch to engage the speed changing clutch with the fast train when the 15 motion changing cam is operated to engage the motion changing clutch with the forward or return train.

19. A machine of the class described, having, in combination, a rotary cutter spindle, 25 a traveling work support, mechanism for advancing, automatically reversing, and returning the work support, and mechanism for stopping the spindle when the support is reversed.

30 20. A machine of the class described, having, in combination, a rotary cutter spindle, a traveling work support, mechanism for advancing, automatically reversing, and returning the work support, mechanism for 35 stopping the spindle when the support is reversed, and means for rendering the stopping mechanism active or inactive at will.

21. A machine of the class described, having, in combination, a rotary cutter spindle, 40 a traveling work support, mechanism for transmitting motion to the work support including mechanism for reversing the direction and mechanism for changing the speed of travel of the support, means for controlling said mechanisms including tripping devices connected to move in unison with the support, and mechanism for stopping the spindle when the direction of travel of the table is reversed and for starting the spindle 45 when the speed is changed from fast to slow.

50 22. A machine of the class described, having, in combination, a rotary cutter spindle, a traveling work support, mechanism for transmitting motion to the work support including mechanism for reversing the direction and mechanism for changing the speed of travel of the support, means for controlling said mechanisms including tripping devices connected to move in unison with the 55 support, mechanism for stopping the spindle when the direction of travel of the table is reversed and for starting the spindle when the speed is changed from fast to slow, and means for rendering the stopping mechanism active or inactive at will.

23. A machine of the class described, having, in combination, a rotary cutter spindle, a traveling work support, mechanism for transmitting motion to the work support including mechanism for reversing the direction and mechanism for changing the speed of travel of the support, means for controlling said mechanisms including tripping devices connected to move in unison with the support, spindle stopping and starting mechanism, and means for operating the latter mechanism to stop the spindle when the reversing mechanism is operated to reverse the support and to start the spindle when the speed changing mechanism is operated to 80 change the speed from fast to slow.

24. A machine of the class described, having, in combination, a rotary spindle, a traveling support, mechanism for transmitting motion to the support including a motion changing clutch and a speed changing clutch, mechanism for shifting the motion changing clutch to reverse the travel of the support including tripping devices connected to move in unison with the support, mechanism for shifting the speed changing clutch to change the speed of travel of the table including tripping devices connected to move in unison with the support, mechanism for stopping and starting the spindle, and controlling means for the latter mechanism connected with the mechanism for shifting the speed changing clutch.

25. A machine of the class described, having, in combination, a rotary spindle, a traveling support, mechanism for transmitting motion to the support including a motion changing clutch and a speed changing clutch, mechanism for shifting the motion changing clutch to reverse the travel of the support including tripping devices connected to move in unison with the support, mechanism for shifting the speed changing clutch to change the speed of travel of the table including tripping devices connected to move in unison with the support, mechanism for stopping and starting the spindle, and controlling means for the latter mechanism connected with the mechanism for shifting the speed changing clutch and with the mechanism for shifting the motion changing clutch.

26. A machine of the class described, having, in combination, a rotary spindle, a traveling support, mechanism for transmitting motion to the support including a motion changing clutch and a speed changing clutch, mechanism for shifting the motion changing clutch to reverse the travel of the support including tripping devices connected to move in unison with the support, mechanism for shifting the speed changing clutch to change the speed of travel of the table including tripping devices connected to move in unison with the support, a driving clutch for the 130

spindle, mechanism for shifting the clutch to stop and start the spindle, controlling means for the latter mechanism operated from the motion changing clutch shifting mechanism to stop the spindle and operated from the speed changing clutch shifting mechanism to start the spindle.

27. A machine of the class described, having, in combination, a rotary cutter spindle,

10 a traveling work support, mechanism for transmitting motion to the work support, including mechanism for reversing the direction and mechanism for changing the speed of travel of the support, means for controlling

15 said mechanisms including tripping devices connected to move in unison with the support, and mechanism for stopping the spindle when the speed is changed from slow to fast and for starting the spindle when

20 the speed is changed from fast to slow.

28. A machine of the class described, having, in combination, a rotary cutter spindle, a traveling support, mechanism through which motion is transmitted to the support

25 including mechanism for alternately changing the speed of the support from fast to slow and slow to fast during its travel, and mechanism for automatically stopping the spindle upon change from slow to fast and

30 starting it upon change from fast to slow.

29. A machine of the class described, having, in combination, a rotary cutter spindle, a traveling support, mechanism through which motion is transmitted to the support

35 including mechanism for alternately changing the speed of the support from fast to slow and slow to fast during its travel, mechanism for automatically stopping the spindle upon change from slow to fast and

40 starting it upon change from fast to slow, and means for rendering the stopping mechanism active or inactive at will.

30. A machine of the class described, having, in combination, a rotary cutter spindle,

45 a traveling support, mechanism through which motion is transmitted to the support including mechanism for alternately changing the speed of the support from fast to slow and slow to fast during its travel,

50 mechanism for reversing the direction of travel of the support, mechanism for automatically stopping the spindle upon a change from slow to fast speed and for starting it upon a change from fast to slow,

55 and mechanism through which a reversal in the direction results in a fast travel of the support.

31. A machine of the class described, having, in combination, a rotary cutter spindle,

60 a reciprocating work support, mechanism for imparting a fast travel to the support during the first part and a slow travel during the last part of its movement in each direction, and mechanism for rotating the

65 spindle in one direction during the forward

and in the opposite direction during the return travel of the support.

32. A machine of the class described, having, in combination, a rotary cutter spindle, a reciprocating work support, mechanism for imparting fast and slow traveling movements to the support in each direction, and mechanism for rotating the spindle in one direction during the slow forward travel of the table and in the opposite direction during the slow return travel of the table.

33. A machine of the class described, having, in combination, a rotary spindle, a traveling support, mechanism, through which motion is transmitted to the table including 80 mechanism for reversing its direction of travel, spindle reversing mechanism through which the spindle may be rotated during the return travel of the support in a direction the reverse of that in which it is rotated 85 during the forward travel of the support.

34. A machine of the class described, having, in combination, a rotary spindle, a traveling support, mechanism through which motion is transmitted to the table including 90 mechanism for reversing its direction of travel, spindle reversing mechanism through which the spindle may be rotated during the return travel of the support in a direction the reverse of that in which it is rotated 95 during the forward travel of the support, and means for rendering the spindle reversing mechanism active or inactive at will.

35. A machine of the class described, having, in combination, a rotary spindle, a traveling support, mechanism through which motion is transmitted to the support including mechanism for reversing its direction of travel and mechanism for imparting fast 100 and slow movements thereto when traveling in either direction, and spindle reversing mechanism operated to reverse the spindle when the travel of the support is reversed.

36. A machine of the class described, having, in combination, a rotary spindle, a traveling work support, mechanism through which motion is transmitted to the support including mechanism for reversing the direction and for changing the speed of travel 115 of the support, means for controlling said mechanism including tripping devices connected to move in unison with the support, and mechanism for reversing the spindle.

37. A machine of the class described, having in combination, a rotary cutter spindle, a work support, mechanism for reciprocating the support, spindle reversing mechanism, spindle starting and stopping mechanism, and means for controlling said mechanisms to impart a fast travel to the support during the first part and a slow travel during the last part of its movement in each direction, to stop the spindle at the end of the travel of the support in each direction, and 120

to start it in a reverse direction upon the shift from fast to slow.

38. A machine of the class described, having, in combination, a rotary cutter spindle, a work support, mechanism for reciprocating the support, spindle reversing mechanism, spindle starting and stopping mechanism, means for controlling said mechanisms to impart a fast travel to the support during 10 the first part and a slow travel during the last part of its movement in each direction, to stop the spindle at the end of the travel of the support in each direction, and to start it in a reverse direction upon the shift from 15 fast to slow, and means for rendering either the spindle reversing mechanism or the spindle stopping mechanism active or inactive at will.

39. A machine of the class described, having, in combination, a rotary spindle, a traveling support, mechanism through which motion is transmitted to the support including a motion changing clutch and a speed changing clutch, mechanism for shifting the motion changing clutch to reverse the direction of travel of the support including tripping devices connected to move in unison with the support, mechanism for shifting the speed changing 25 clutch including tripping devices connected to travel in unison with the support, and a spindle reversing clutch operated from the mechanism for shifting the motion changing clutch.

40. A machine of the class described, having, in combination, a rotary spindle, a traveling support, mechanism through which motion is transmitted to the support including a motion changing clutch and a speed changing clutch, mechanism for shifting the motion changing clutch to reverse the direction of travel of the support including tripping devices connected to move in unison with the support, mechanism for 45 shifting the speed changing clutch including tripping devices connected to travel in unison with the support, a spindle reversing clutch operated from the mechanism for shifting the motion changing clutch, and means for at will connecting or disconnecting the reversing clutch with said clutch shifting mechanism.

41. A machine of the class described, having, in combination, a rotary spindle, a traveling support, mechanism through which motion is transmitted to the support including a motion changing clutch and a speed changing clutch, mechanism for shifting the motion changing clutch to reverse 55 the direction of travel of the support including tripping devices connected to move in unison with the support, mechanism for

shifting the speed changing clutch including tripping devices connected to travel in unison with the support, a spindle reversing clutch operated from the mechanism for shifting the motion changing clutch, a spindle stopping and starting clutch, and mechanism for shifting said latter clutch controlled from the mechanisms for shifting the motion and speed changing clutches.

42. A machine of the class described, having, in combination, a reciprocating work support, two oppositely arranged cutters mounted transversely of the support and out of alignment in the direction of travel of the support, and mechanism for rotating the cutters to cut in the same relation to the feed.

43. A machine of the class described, having, in combination, a reciprocating work support, a spindle extending transversely over the support, two oppositely acting cutters mounted on the spindle, and mechanism for rotating the spindle during the return of the support in a direction the reverse of that in which it is rotated during the advance of the support.

44. A machine of the class described, having, in combination, a traveling support, two oppositely arranged cutters mounted transversely of the support and out of alignment with each other in the direction of travel of the support, mechanism for imparting a fast feed to the support during the first part of its travel and a slow feed during the remainder of its travel in each direction, and mechanism for rotating the cutters to cut in the same relation to the feed.

45. A machine of the class described, having, in combination, a traveling support, a mechanical train through which motion is transmitted to the support including a motion changing clutch and a speed changing clutch so arranged in the train that motion is transmitted from one clutch through the other, mechanism controlled by tripping devices connected to move in unison with the support for shifting the motion changing clutch when the speed changing clutch is either in high or in slow speed position.

46. A machine of the class described, having, in combination, a traveling support, a mechanical train through which motion is transmitted to the support including a motion changing clutch, slow and fast speed trains driven from said clutch, a speed changing clutch for connecting either the fast or the slow speed train with the support, and mechanism including tripping devices connected to move in unison with the support for shifting the clutches.

CHARLES A. RICH.
